E. A. CRAWFORD

ARTICLE CARRYING BAG

Filed Aug. 11, 1922

UNITED STATES PATENT OFFICE.

EARL A. CRAWFORD, OF HUDSON FALLS, NEW YORK, ASSIGNOR TO UNION BAG & PAPER CORPORATION, OF HUDSON FALLS, NEW YORK, A CORPORATION OF NEW JERSEY.

ARTICLE-CARRYING BAG.

Application filed August 11, 1922. Serial No. 581,184.

To all whom it may concern:

Be it known that I, EARL A. CRAWFORD, a citizen of the United States, residing at Hudson Falls, in the county of Washington and State of New York, have invented certain new and useful Improvements in Article-Carrying Bags, of which the following is a specification.

The present invention relates to improvements in bags or receptacles, and more especially to those of the kind adapted for use by shoppers and others for carrying dry-goods, notions and other relatively small articles. The primary object of the invention is to provide a novel and improved bag or receptacle of this character which embodies means by which it can be easily and quickly closed or secured in closed condition, the closing means also providing means by which the bag or a number of such bags can be conveniently carried on the finger or fingers without risk of dropping or losing any of the bags or the contents thereof.

To these and other ends, the invention consists in certain improvements and combinations and arrangements of parts, all as will be hereinafter more fully described, the features of novelty being pointed out particularly in the claims at the end of the specification.

In the accompanying drawing:—

Figure 1 is a perspective view of a notion-carrying bag constructed in accordance with the preferred embodiment of the invention, the bag being shown in closed condition;

Figure 2 is a perspective view of the upper portion of the bag as shown in Figure 1, but with the lip or closure unsecured and open; and

Figure 3 represents a section through the bag on the line 3—3 of Figure 1, the bag, however, being in unfastened and open condition.

Similar parts are designated by the same reference characters in the several views.

The bag, which may be made in different sizes, comprises in the present instance, a front section 1, a rear section 2 which is continuous with the front section at one vertical side of the bag and is secured thereto at the opposite vertical side by a side seam 3, a fold 4 at the bottom of the bag, which closes it at this point, and a lip 5 which, in the present instance, is a continuation of the

front section 1 and is foldable along the hinge line 6 in a direction downwardly and against the upper edge of the rear section 2 to close the bag. The bags which are preferably made from a continuous web of paper of suitable texture or strength, may be made up of single blanks cut successively from such a web, the lip 5 of one bag blank being advantageously cut partially from the lower edge of the front section of an adjacent bag blank, leaving a notch 7 in the lower edge of the front section 1, which, however, is covered and closed by the fold 4, thus economizing in paper or material, and it is also preferable to cut a notch 8 in the upper edge of the rear section 2 for a purpose to be hereinafter described, the cutting of this notch 8 in the rear section of one bag blank causing a tab 9 to be formed on the lower edge of the rear section of an adjacent bag blank in the web.

According to the present invention, cuts 10 are formed in the lip 5 above or adjacent to the hinge line 6 of this lip, the intermediate portions of these cuts being deflected or offset upwardly, substantially as shown. These cuts cause the material of the lip between the cuts to project upwardly as a continuation of the front section 1 of the bag when the lip 5 is folded downwardly about its hinge line 6 and into closed position against the rear section 2, this upstanding portion 11 forming, in effect, a loop. In order to afford sufficient strength for this loop, it is preferable to paste a reinforcement 12, which may be composed of relatively tough paper or other suitable flexible material, on to the inner side of the front section 1 of the bag and to form the cuts 10 through this reinforcement, as well as through the lip 5, the loop 11 being then formed jointly by material of the lip 5 and also material of the reinforcement 12. When the lip 5 is in its open or unfolded condition, as is shown substantially in Figures 2 and 3, the loop 11 will lie substantially in the plane of the lip or of the front section 1 of the bag, and hence will not form an obstruction to the introduction or removal of articles relatively to the bag. Means is provided at the rear of the bag to cooperate with the lip 5 and the loop 11 to lock or secure the lip in closed position and to provide means for carrying the bag in a manner which will prevent ac-

cidental opening of the lip. Preferably and as shown in the present instance, a flap 13 has its lower end pasted or otherwise suitably secured to the rear side of the rear section 2 of the bag at a point below the lowermost edge of the lip 5, when the latter is folded or in closed position, the flap 13 extending upwardly for a suitable distance where it is unpasted relatively to the rear section 2 of the bag, so that this flap can be pulled rearwardly to permit opening or closing of the lip 5 without interference, and the upper or free end of this flap has a loop 14 attached thereto. This loop 14 is preferably composed of a stout cord which is suitably secured to the upper free end of the flap 13, as for example, by folding or doubling the upper free end of the flap 13 about the lower portion of the loop 14 and pasting this folded or doubled portion of the flap upon the loop and also upon the body of the flap. The loop 14 is of such a length that it is capable of projecting above the line of fold 6 a distance greater than that of the loop 11.

25 The mode of using a bag constructed as herein described is as follows: When the bag is in the condition shown in Figures 2 and 3, with the lip 5 in open position, articles can be inserted into the bag or removed therefrom without obstruction. The bag is closed by pulling rearwardly the loop 14 and the free or unattached portion of the flap 13, then swinging the lip 5 rearwardly and downwardly against the upper portion 30 of the rear section 2 of the bag, and finally inserting the loop 14 through the loop 11, which latter then projects above the hinge line 6 of the lip 5 substantially as a continuation of the front section 1 of the bag.

35 The part of the loop 14 which projects above the loop 11 provides a finger-piece adapted to be applied to the finger of the shopper and when the bag is carried in that manner it is impossible for the lip 5 to open, owing 40 to the overlapping of this lip by the flap 13, and moreover the tension exerted on the loops 11 and 14, due to the weight of the bag and its contents, tends to draw the loops 11 and 14 inwardly or toward one 45 another, thus producing compression upon the lip 5 which will securely retain it in closed condition. Obviously, a number of bags constructed as herein described can be conveniently carried on the finger or fingers 50 of the shopper without risk of dropping or losing any of the bags or the contents thereof.

The notch 8 is preferably formed in the upper edge of the back section 2 opposite 60 to the loop 11 in order to provide a clearance or passageway to facilitate the insertion of the loop 14 through the loop 11.

I claim as my invention:—

1. A bag of the character described comprising front and back sections closed at

the bottom, a lip attached to one of said sections and foldable upon the other section to close the mouth of the bag, incisions being made in the lip adjacent to its line of fold to form a relatively short loop which projects upwardly above said line of fold when the lip is folded, and a locking and carrying member adapted to overlie the lip when closed and capable of insertion through and extending upwardly beyond 75 said loop.

2. A bag of the character described comprising front and back sections one of which has a lip attached thereto which is foldable onto the other section to close the bag, the lip having incisions adjacent to its line of fold which produce an upstanding loop when the lip is folded into closed position, and a second loop attached to the other section at a point below the lowermost edge of the loop when folded thereon and adapted to overlie the lip when folded and to extend through and above the loop first-mentioned to secure the lip in closed position and to form a carrying handle.

3. A bag of the character described comprising front and back sections, the former having a lip attached thereto and foldable onto the back section to close the respective end of the bag, the bag having a pair of incisions the intermediate portions of which are deflected upwardly away from the line of fold of the lip to form an upstanding loop which is a substantial continuation of the front section of the bag when the lip is folded, and means attached to the back section of the bag and capable of overlying the lip when folded and of extending through and projecting upwardly beyond the loop first-mentioned to secure the lip in closed position and to provide a carrying member.

4. A bag of the character described comprising front and back sections, the former having a lip attached thereto along a line about which it is foldable onto the back section, a reinforcement applied to the front section and lip, a pair of incisions being formed in the lip and reinforcement adjacent to the line of fold to produce a loop which projects above the line of fold of the lip when the latter is folded, and means on the back section to overlie the lip and to extend through said loop to secure the lip in folded position and to provide a carrying handle.

5. A bag of the character described comprising front and back sections, the former having a lip attached thereto along a line about which it is foldable onto the back section to close the bag, cuts being formed in the lip adjacent to said line to produce a loop which projects upwardly above said line as a substantial continuation of the front section when the lip is folded, the

adjacent edge of the rear section having a notch formed therein opposite to the loops, and a second loop attached to the back section below the lowermost edge of the lip 5 and unattached relatively to the area of the back section onto which the lip is foldable, said second loop being adapted to overlie the outer rear side of the lip and capable of insertion through said notch and the loop 10 first mentioned to secure the lip in folded

position and to provide a carrying finger piece above the first-mentioned loop.

In testimony whereof I have hereunto set my hand in presence of two subscribing witnesses.

EARL A. CRAWFORD.
